UNITED STATES PATENT OFFICE.

F. ROBERT SEIDENSTICKER, OF MERIDEN, CONNECTICUT, ASSIGNOR TO THE
BRADLEY & HUBBARD MANUFACTURING COMPANY, OF SAME PLACE.

DESIGN FOR A FENDER.

SPECIFICATION forming part of Design No. 16,910, dated September 21, 1886

Application filed July 26, 1886. Serial No. 209,180. Term of patent 5 years.

To all whom it may concern:

Be it known that I, F. ROBERT SEIDENSTICKER, of Meriden, in the county of New Haven and State of Connecticut, have invented a new Design for a Fire-Fender; and I do hereby declare the following, when taken in connection with accompanying drawing and the letters of reference marked thereon, to be a full, clear, and exact description of the same, and which said drawing constitutes part of this specification, and represents a perspective view.

This invention relates to a design for a fire-fender; and it consists in the configuration and ornamentation, as shown in the accompanying illustration.

The frame consists of a lower bar, B, and upper bar, C, and a series of upright spindles, D. A section of the uprights between the lower and upper bar is represented as twisted, and a section of the upper bar between the uprights is also represented as twisted. In the spaces between the uprights is the representa-

tion of open scroll-work, and, as here shown, there is an upwardly-projecting center piece, 25 represented as a twisted bar terminating in a scroll at each end above the upper bar; but this center ornament may be omitted or changed without departing from the spirit of this design. 30

I claim—

The herein-described design for a fire-fender, consisting of the lower bar, B, and upper bar, C, parallel with each other, a series of spiral vertical spindles, D, between the bars, the 35 section of the spindles between the two bars represented as twisted, and the section of the upper bar between the spindles represented as twisted, and with the representation of open scroll-work in the spaces between the bars and 40 spindles, as shown in the accompanying illustration.

F. ROBERT SEIDENSTICKER.
